F. J. CHAMPLIN

COMBINED TANK AND CORE FOR INDUCTION APPARATUS

Filed Aug. 16, 1921

Inventor:

Franklin J. Champlin,

by *Albert L. Davis*
His Attorney.

UNITED STATES PATENT OFFICE.

FRANKLIN J. CHAMPLIN, OF PITTSFIELD, MASSACHUSETTS, ASSIGNOR TO GENERAL ELECTRIC COMPANY, A CORPORATION OF NEW YORK.

COMBINED TANK AND CORE FOR INDUCTION APPARATUS.

Application filed August 16, 1921. Serial No. 492,751.

To all whom it may concern:

Be it known that I, FRANKLIN J. CHAMPLIN, a citizen of the United States, residing at Pittsfield, county of Berkshire, State of Massachusetts, have invented certain new and useful Improvements in Combined Tanks and Cores for Induction Apparatus, of which the following is a specification.

My invention relates to induction apparatus and more particularly to an improved form of combined tank and core adapted to contain a quantity of cooling liquid, such as oil, to absorb and carry away heat generated in the core during the operation of the apparatus.

One object of the invention is to provide a hollow laminated core so constructed as to be impervious to oil or other cooling liquid, the core thus being adapted to constitute a portion of the oil retaining structure or tank. This feature of the invention permits a reduction in the cost of labor and material necessary in the provision of frame and tank structure provided in such apparatus for the purpose of supporting the core and holding the oil or other cooling liquid. A further object of the invention is to provide suitable tank structure so joined to and associated with the laminated core that together the core and tank structure may form a tank or container to retain a body of liquid for cooling and insulation purposes.

The invention is illustrated in the accompanying drawing as embodied in the construction of an induction regulator, although it will be apparent that the invention may be applied with advantage in the construction of other forms of apparatus in which the hollow laminated cores are used.

In the induction regulator shown in the drawing, the laminated core 1 is built up of thin soft iron annular rings secured together by some suitable adhesive substance, such as shellac, or some suitable phenol condensation product such as bakelite, which will not only secure the laminations firmly together, but will also seal the joints between them efficiently against any leakage of the cooling liquid. This construction may be attained by shellacking both sides of each ring, allow-

ing the shellac to dry, stacking the rings together in a temporary frame, pressing the rings firmly together, heating the rings and shellac by inserting the rotor and over-ex- 55 citing it or otherwise, and allowing the rings and shellac to cool and the shellac to solidify. The top and bottom core flanges, 2 and 3, are secured to the core in a similar manner so as to provide tight joints. The bottom 60 plate 4, formed with a step bearing 5 for a rotor, is joined to the bottom core flange 3 by a cylindrical tank section 6, these parts being shown bolted together to provide tight joints. A corrugated tank section 7 with a 65 bottom flange 8 and a top flange 9 is bolted to the top core flange 2 and a cover 10, formed with a bearing 11 for the rotor, is provided above the flange 9.

The parts described above enclose a space 70 in which the rotor 12 may revolve and which is adapted to contain a body of cooling liquid, or oil, which will absorb heat generated in the core and convey it to other portions of the structure, principally to the corrugated tank section 7, where it is given up 75 and conveyed to the outside air.

It will be seen that the laminated core 1 forms a portion of the tank wall and that this construction therefore obviates the necessity of providing a separate entire tank to hold the oil. The outer surface of the core 1 is also exposed directly to the outside air and much of the heat generated in the core is therefore dissipated directly to the 85 outside air from this surface.

Having illustrated and described the details of one form of my invention, what I claim as new and desire to secure by Letters Patent of the United States is:

1. An induction apparatus including a hollow laminated core, the laminations of the core being secured together by an adhesive substance to render the joints between said laminations impervious to a cooling 95 liquid contained within said core.

2. An induction apparatus including a hollow laminated core adapted to surround a body of cooling liquid, the joints between the laminations of the core containing a substance to render said joints impervious to the cooling liquid, and means secured to the 100

core and cooperating therewith to form a tank for the cooling liquid.

3. An induction apparatus including a hollow laminated core adapted to surround a body of cooling liquid, the laminations of the core being secured together by an adhesive substance to render the joints between

said laminations impervious to the cooling liquid, and means secured to the core and cooperating therewith to form a tank for the cooling liquid. 10

In witness whereof, I have hereunto set my hand this 12 day of August, 1921.

FRANKLIN J. CHAMPLIN.

Certificate of Correction.

It is hereby certified that in Letters Patent No. 1,548,658, granted August 4, 1925, upon the application of Franklin J. Champlin, of Pittsfield, Massachusetts, for an improvement in "Combined Tanks and Cores for Induction Apparatus," an error appears in the printed specification requiring correction as follows: Page 1, strike out lines 91 to 96 comprising claim 1, and insert the following as claim 1:

1. An induction apparatus including a hollow laminated core adapted to surround a body of cooling liquid, the joints between the laminations of the core containing a substance to render said joints impervious to the cooling liquid.;
and that the said Letters Patent should be read with this correction therein that the same may conform to the record of the case in the Patent Office.

Signed and sealed this 13th day of October, A. D. 1925.

[SEAL.]

KARL FENNING,
Acting Commissioner of Patents.
